UNITED STATES PATENT OFFICE.

CRAWFORD M. FAIRBANKS, OF PAWTUCKET, RHODE ISLAND.

FILE.

SPECIFICATION forming part of Letters Patent No. 253,858, dated February 21, 1882.

Application filed October 10, 1881. (No model.)

To all whom it may concern:

Be it known that I, CRAWFORD M. FAIRBANKS, of Pawtucket, county of Providence, in the State of Rhode Island, have made certain new and useful Improvements in Files; and I do hereby declare that the following specification, taken in connection with the drawings making a part of the same, is a full, clear, and exact description thereof.

10 Figure 1 is a view of one side of the file. Fig. 2 is a view of the reverse side. Fig. 3 shows the safe edge.

My invention relates to what is known in the market as a "safe-edge file."

15 It consists in the arrangement of the upper and over cuts, both as to angle and precedence, during process of manufacture, and has for its object the drawing of the file toward one and the same safe edge without regard to the side 20 of the file used.

In the drawings, A, Figs. 1, 2, and 3, is the safe edge of the file, which is left smooth, without having any teeth cut thereon, while the other edge, B, is cut as in ordinary files.

25 The ordinary flat safe-edge file now in use is made with two cuts, called respectively an "over cut" and an "upper cut," the former being a heavy cut and the latter a light cut. The over or heavy cut is first made and is put on 30 at an angle with the file-blank. The heavy cut would naturally actuate and control the "draw" of the file in one direction or another, according to the angle of such over cut to the file-blank, were it not that the subsequent upper cut destroyed to a great extent such a re-

sult through the interruption of the oblique lines. Such a tendency to draw as may remain after the addition of the upper cut will carry the file to the right and toward the safe edge when it is used upon one side, and when 40 reversed will carry it in the same direction, but toward the cut edge, which by the reversal has taken the place of the safe edge.

In my invention the file draws in one direction while engaged upon one side and in the 45 opposite direction upon the other, but always toward the safe edge. I make the upper cut the coarse or heavy cut and the over cut the fine cut. The upper or heavy cut upon the blank is cut at an angle from left to right from 50 the shank toward the tip C, Fig. 1, upon one side, and from the tip toward the shank D, Fig. 2, upon the reverse. The upper cut on my improved file takes the place of the over cut in the old file at the same angle upon one 55 side, and the upper cut takes the place of the over cut at its own angle upon the reverse. It will now be readily seen that the upper cut will control the draw of the file, and will at all times carry it toward the safe edge.

60 What I claim as my invention, and desire to secure by Letters Patent, is—

The safe-edge file herein described, having a fine over cut and a coarse upper cut, as and for the purposes specified.

CRAWFORD M. FAIRBANKS.
